UNITED STATES PATENT OFFICE.

ANTON SWIENTEK, OF CHICAGO, ILLINOIS.

DESIGN FOR A PICTURE, MIRROR, OR LIKE FRAME.

59,303.

Specification for Design.

Patented Oct. 4, 1921.

Application filed July 6, 1921. Serial No. 482,856. Term of patent 7 years.

To all whom it may concern:

Be it known that I, ANTON SWIENTEK, a citizen of Poland, residing at Chicago, in the county of Cook and State of Illinois, have invented a new, original, and ornamental Design for Picture, Mirror, or like Frames, of which the following is a specification, reference being had to the accompanying drawing, forming part thereof.

The figure is a view in perspective of a picture, mirror or like frame, showing my new design.

I claim:

The ornamental design for a picture, mirror, or like frame, as shown.

ANTON SWIENTEK.
